NECKTIE

John F. Kossow, 3513 50th St. S.,
Tampa, Fla. 33619

Filed Dec. 1, 1966, Ser. No. 4,871

Term of patent 14 years

(Cl. D2—355)

FIG. 1 is a front perspective view of a necktie showing my new design;

FIG. 2 is a front elevational view thereof as it appears in wearing position tied in a four-in-hand knot, the necktie has been shown broken away for convenience of illustration.

FIG. 3 is a side elevational view thereof.

I claim:

The ornamental design for a necktie, as shown and described.
